CIGARETTE HOLDING RING

Gerald A. Maurette, Medford, Mass.

Application July 10, 1933. Serial No. 679,809

4 Claims. (Cl. 63—1)

This invention relates to a finger ring, one of the objects being to provide an article of this kind with which is combined a means for gripping a cigarette so that it can be held to the mouth without danger of discoloring the fingers.

A further object is to provide a finger ring having a setting so constructed as to be capable of opening to positions to receive a cigarette between them.

Another object is to provide a finger ring which can be easily actuated to move the members of the setting into or out of cigarette-gripping position.

Another object is to provide a structure of simple and compact construction, it being possible readily to incorporate the improvements in a ring which is not of unusual size and which will not have an objectionable appearance.

With the foregoing and other objects in view which will appear as the description proceeds, the invention consists of certain novel details of construction and combinations of parts hereinafter more fully described and pointed out in the claims, it being understood that changes may be made in the construction and arrangement of parts without departing from the spirit of the invention as claimed.

In the accompanying drawing the preferred form of the invention has been shown.

In said drawing:

Figure 1 is a plan view of the finger ring showing the box and setting.

Figure 2 is a section on line 2—2, Figure 1.

Figure 3 is a section on line 3—3, Figure 1.

Figure 4 is a plan view of a portion of the box showing one of the members of the setting opened outwardly to gripping position.

Referring to the figures by characters of reference 1 designates the box of a ring 2, it being understood that the same can be of any desired configuration and size. Arranged within the open top 3 of the box are separate holders 4, each of which carries a stone 5 or other set. These holders are mounted to swing on cross pins 6 anchored within the box 1. Normally the

holders come together along their inner sides as shown at 7 in Figure 2, they being held yieldingly in these positions by springs 8. In the structure illustrated coiled springs are used, each coil being mounted on one of the pins 6 and anchored at one end to the pin as shown at 9 while its other end forms an arm 10 normally bearing downwardly upon a shelf or flange 11 constituting a part of the holder thereabove.

Formed on or secured to each of these shelves

or flanges is a jaw 12 normally housed in an inverted position within the box 1 as shown in Figure 2.

Depending from the outer side of each holder 4 is a bail 13 of rigid material which is loosely engaged by a slotted arm 14 extending laterally and upwardly from a cross arm 15. This cross arm rests on the bottom of the box and is pivoted at its center on a rivet 16 or the like located equidistant from the pins 6.

The respective ends of cross arm 15 project through slots 17 in opposite sides of the box 1 and can be suitably finished so as to provide a finger piece 18 at each end of the cross arm.

Normally the holders 4 are closed together as shown in Figures 1 and 2 at which time the ring has the appearance of an ordinary finger ring. While two oblong stones or sets have been shown in position in these holders it is to be understood that sets of other shapes and styles could be used.

Should it be desired to employ the ring for the purpose of holding a cigarette while being smoked, the wearer of the ring would merely press against one of the finger pieces 18 to move it out of normal position. This would cause cross arm 15 to swing about its fulcrum 16 so that slotted arms 14 would pull upon the respective bails 13 and swing them toward each other from the full line position shown in Figures 1 and 2 to the dotted line position shown in Figure 2. A cigarette C can then be placed between the elevated jaws 12 and by releasing finger piece 18 the holders 4 will be moved slightly toward each other by springs 8 until the jaws 12 firmly grip the cigarette. While the cigarette is thus held it can rest within rounded recesses 19 provided in opposite sides of the box 1. When it is desired to release the burned cigarette the finger piece 18 is pushed so as to move jaws 12 apart. The cigarette will then fall from between the jaws and by releasing the finger piece the springs will return holders 4 to their normal positions.

Obviously various modifications of the structure can be made within the scope of what is claimed.

What is claimed is:

1. In a finger ring the combination with a box, of opposed members movably mounted therein and normally constituting closures for the box, means for swinging the members outwardly and apart to receive a cigarette therebetween, and means for actuating said members to yieldingly grip an interposed cigarette.

2. A finger ring including a box, separate mem-

bers hingedly connected thereto and cooperating to provide a set for the ring, means for simultaneously swinging the members outwardly relative to the box and from each other to provide a cigarette-receiving space therebetween, and means for exerting a yielding pressure against said members thereby to grip an interposed cigarette.	bers outwardly relative to the box and positioning the jaws to receive a cigarette therebetween.
5	4. A finger ring including a box, a set therefor comprising opposed hingedly mounted members normally extended across and substantially closing the box, jaws carried by the members and normally concealed within the box, and means extending from the box for swinging the members
